UNITED STATES PATENT OFFICE.

JAMES N. MAYHEW, OF MINNEAPOLIS, MINNESOTA, ASSIGNOR TO JAMES N. MAYHEW COMPANY, INC., OF MINNEAPOLIS, MINNESOTA, A CORPORATION OF MINNESOTA.

TOP-TREE FOR SHOES.

1,258,133.

Specification of Letters Patent.

Patented Mar. 5, 1918.

Application filed October 23, 1916. Serial No. 127,122.

To all whom it may concern:

Be it known that I, JAMES N. MAYHEW, a citizen of the United States, residing at Minneapolis, in the county of Hennepin and State of Minnesota, have invented certain new and useful Improvements in Top-Trees for Shoes; and I do hereby declare the following to be a full, clear, and exact description of the invention, such as will enable others skilled in the art to which it appertains to make and use the same.

My invention relates to top trees for shoes; and, to this end, it consists of the novel devices and combination of devices hereinafter described and defined in the claims.

The invention is designed for use in connection with shoes, on display in windows or elsewhere, and has for its object to provide means for holding up or supporting the top of a shoe and its tongue in order to give the shoe on display, a smooth and neat appearance.

In the accompanying drawings, which illustrate the invention, like characters indicate like parts throughout the several views.

Referring to the drawings:—

Figure 1 is a perspective view of a shoe having the invention applied therein;

Fig. 2 is a side elevation of the shoe with some parts broken away to expose the invention applied therein; and

Fig. 3 is a view principally in plan with some parts sectioned on the line 3—3 of Fig. 2.

The device comprises a revoluble post 1, a head 2, front arm 3, and a rear arm 4. The post 1 is provided with a conical lower end 5 adapted to engage the insole of a shoe Z and affords the pivot on which said post 1 revolves. The upper end of the post 1 is squared at 6 to receive a wrench or key, not shown, by which the post 1 may be revolved. Screw threads 7 are formed on the post 1 throughout its entire length between the conical point 5 and squared upper end 6.

The head 2 has screw-threaded engagement with the post 1 and may be vertically adjusted by revolving said post. The forward end of the head 2 is bifurcated at 8 and the lower end of the arm 3 is inserted between the prongs thereof and pivoted thereto for vertical swinging movement. As

shown, the arm 4 is integrally formed with the head 1, at a diametrically opposite point from the bifurcation 8 and projects upwardly and rearwardly therefrom. On the upper end of the arm 4 is an upwardly and rearwardly projecting barb 9 adapted to enter the top of the shoe Z at the back thereof. A pair of upwardly diverging barbs 10 are rigidly secured to the upper end of the arm 3 and extend transversely of the head 2. These barbs 10 are adapted to be inserted through the tongue of the shoe Z and into the upper pair of eyelets in the top of said shoe.

With the barbs 9 and 10 engaging the shoe top as described, the post may be rotated to elevate the head 2, which is held against rotation by the engagement of said barbs with the shoe. Under the elevating movement of the head 2, produced by rotating the post 1, which is supported on the sole of the shoe as a base of resistance, the top of the shoe is stretched from top to bottom and the longitudinal edges thereof held parallel. At the same time the tongue of the shoe is stretched lengthwise and held folded, by the arm 3 and prongs 10, between the parallel sides of the shoe top. The elevating movement of the head 2 also causes the arm 3 to swing outwardly, thereby stretching the shoe top longitudinally of the shoe. With the shoe top and tongue thus held, the shoe is given a smooth and neat appearance for display purposes and at the same time the device is entirely concealed within the shoe.

The above described device, while extremely simple and of comparatively small cost to manufacture, is easy to apply in working position or remove therefrom and in actual usage has proven highly efficient for the purpose had in view.

What I claim is:—

1. A top tree for shoes comprising a post and a head vertically adjustable thereon, said head having a pair of rigid arms with barbs arranged to engage a shoe top, one of said arms being integrally formed with said head and the other thereof being secured thereto for vertical swinging movement.

2. A top tree for shoes comprising a post and a head vertically adjustable thereon, said head having a pair of rigid arms, one of said arms being integrally formed with said

head and provided with a barb arranged to engage a shoe top at the back thereto, and the other of said arms being secured to the head for vertical swinging movement and having a pair of upwardly diverging barbs arranged to engage opposite sides of the shoe top at the front thereof.

Copies of this patent may be obtained for five cents each, by addressing the "Commissioner of Patents, Washington, D. C."

In testimony whereof I affix my signature in presence of two witnesses.

JAMES N. MAYHEW.
